UNITED STATES PATENT OFFICE

2,182,233

DEVICE FOR INCREASING EFFECTIVENESS
OF NEON SIGNS

Joseph H. Pearlman, Des Moines, Iowa

Application September 7, 1937, Serial No. 162,718

4 Claims. (Cl. 40—130)

My invention relates to a structure for use in connection with signs or similar devices employing tubular illuminant sources, such as the common neon tubing or the like.

It is the purpose of my invention to provide an improvement in the usual neon type sign whereby the proportions of the letters comprising the sign as they appear to the eye can be improved, and the effectiveness of the sign thereby increased.

Another object is to provide means whereby the amount of effective illumination from the sign may be increased.

More particularly an object is to provide means whereby the stroke of a letter or the width of the stem of a letter as it appears to the observer's eye may be increased.

Another particular object is to provide means whereby a so-called "spectacular" sign may be constructed at much less cost than by the ordinary method.

Another object is to furnish means for utilizing light emanating from the sides and back of the illuminant tube which would otherwise not reach the eye of the observer and would consequently be of no effect and could be considered wasted.

With these and other objects in view, my invention consists in the construction, arrangement and combination of the various parts of my device, whereby the objects contemplated are attained as hereinafter more fully set forth, pointed out in my claims and illustrated in the accompanying drawing, in which:

Figure 1 is a front view of the letter I of a neonized sign of the conventional type.

Figure 2 is a horizontal cross section on the line 2—2 of Figure 1.

Figure 3 is a front view of the letter I of a neonized sign embodying my invention.

Figure 4 is a horizontal cross section taken on the line 4—4 of Figure 3 showing a form of my invention adapted for surface mounting.

Figure 5 is a front view of the letter S of a sign showing how my invention is applied to a curved letter.

Figure 6 is a horizontal cross section on the line 6—6 of Figure 5 showing a form of my invention as adapted for sub-surface mounting in cut-outs.

Figures 7, 8 and 9 are diagrammatic representations of modified forms of cross section embodying my invention.

In the ordinary type of neon sign, a luminous tube 10 in the shape of a letter, in Figure 1 the

letter I is mounted by suitable insulating supports to the base portion 14 of the sign. The insulating supports for the neon tube are omitted from the drawing inasmuch as they are not a part of my invention and would unnecessarily confuse the disclosure in the drawing. The letter may be outlined by a channel member 16 having a bottom portion 18 and side flanges 20. The inner surfaces of the channel are painted in some color which contrasts with the color 10 used on the front surface of the base portion 14 and the outer surfaces of the flanges 20. The contrast in colors serves to give breadth and the channel gives apparent depth to the letters in daytime illumination. At night, however, inasmuch as the painted surfaces do not have much reflecting power for the light from the neon tubes, the principal impression given to the eye is that 15 of the glowing neon tubes themselves and these of necessity are very much narrower than the 20 channels, or where channels are not used, than the painted letters on the back of the sign. The channel or painted letters are sometimes hardly visible by the neon illumination at night, particularly at great distances, and consequently do 25 not contribute substantially to the night time effectiveness of the sign.

In a properly proportioned sign letter which is pleasing to the eye, the stroke or width of the stem of the letter should be approximately one-fifth the height of the letter. A letter five feet high, for example, should have a stroke one foot wide.

The limitations of gaseous discharge tubes, such as the neon tubes used in signs, are such that the tubes are made of the order of one inch or less in diameter. In view of this fact it will be readily seen that in large signs having letters several feet in height, where a single neon tube is used in the form of the letter, the 5 to 1 ratio of height to stroke cannot be maintained. Under night time or low visibility conditions, the stroke of the letters will appear to the eye to be the diameter of the tubing and therefore will be much less than one-fifth the height of the letters. Because of the narrow, stringy character of the letter it does not have the pleasing quality and effectiveness of a bold, full stroke letter.

To remedy this weakness it has been customary in making large signs, or "spectaculars," to 50 outline the full stroke letter in gas tubing instead of running a single tube down the center of the stroke. Or, in some cases, a plurality of tubes running close together have been used to completely fill the stroke of the letter. Either 55

of these methods, while achieving the desired proportions of the neonized letter, obviously involves great increases both in the original cost and in the operating cost of the sign, as compared to the single tube style.

By the use of my invention the effect of a full stroke letter may be obtained with a single neon tube with a relatively small increase in the first cost of the sign and no increase in operating cost. 10 My invention involves a reflector formed in the shape of the letter and having multiple mirror facets arranged across the stroke of the letter, parallel to the neon tubing in the center, and at such an angle that each facet reflects an image of the tube to the eye of the observer.

Figure 3 illustrates my invention embodied in a letter I of a sign. The neon tube 22 is mounted on suitable supports, not shown, and is backed by a reflector referred to generally as 26. The 20 reflector 26 has the outline of the desired letter and the proper proportion of stroke to height. The reflector has portions 28, 30, 32, 34 and 36, each comprising reflecting surfaces substantially parallel to the neon tube and each being arranged 25 to reflect an image of the tube, as indicated by the rays represented by the dotted lines 37 in Figure 4. The reflected images are shown in dotted lines at 35 in Figure 3. The effect, to the observer's eye, is substantially the same as if the 30 letter were composed of a plurality of parallel neon tubes within the space between adjacent pairs of images on opposite sides of the tube equal to each other. At a distance, because of the limited resolving power of the eye, the separate bands 35 of the reflected images seem to blend in one broad stroke in a letter of the proper proportions.

Figure 5 shows how my invention will be applied to other letters, the letter S being represented in the drawing. The mirror facets will follow the 40 curves or straight portions of the letter, maintaining the proper angle to the center light or neon tube.

The reflectors may be cast in glass or other moldable or plastic material and may be clear or colored, depending upon the effect desired. They 45 may be silvered or otherwise provided with reflecting surfaces on either the inner or outer faces. The reflectors may also be formed of metal and have reflector surfaces provided by 50 plating or polishing.

My invention is adapted to be used in various types of signs. For example, it may be used in cut-out signs, and the reflector may be inserted in a letter-shaped aperture, such as 38 of Figure 55 6, cut in the base portion 38 of the sign, in the same manner as the common opalite glass sign letters. In Figure 6 the reflector is shown as having flanges 40 through which screws 42 may be passed for attaching the reflector to the base 60 38.

The reflector may also be made in a pattern suitable for surface mounting, as illustrated for example in Figure 4. In this case the flanges are turned inwardly as at 42 and serve principally 65 for reinforcement. The reflector is mounted on the base 44 by screws 46 passed through the reflector along its center line. Either the cut-out mounting of Figure 6 or the surface mounting of Figure 4 may be used in connection with channels and, by way of illustration, flanges have 70 been shown at 48 in Figure 4 to provide channel formations.

In order not to complicate the drawing, only two inclined reflecting surfaces 28, 30 and 34, 75 36 have been shown on each side of the center

portion 32. However, the reflector may incorporate any suitable number of such surfaces and I do not wish to be limited to the number shown in the drawing. The reflecting surfaces may be of plane character, such as indicated by the straight line portions in Figure 6, or they may be curved. I have shown diagrammatically in Figures 7, 8 and 9 modified forms of my reflector in which the reflecting surfaces are curved. Figure 7 shows a particular modification in which the surfaces are convex as at 50. Figure 8 represents a modification in which the surfaces are concave as at 52. Figure 9 is a modification wherein both convex and concave surfaces are employed, shown at 54 and 56. Curved surfaces may have greater advantages in producing the desired effect of this sign when it is viewed from an angle as distinguished from a position straight in front of the sign. Increasing the number of similar reflecting surfaces over the number shown in my drawing, would have the desirable result of reflecting a greater number of images of the neon tube and it is obvious that the greater number of images, closer together, would apparently blend into a full stroke letter at less distance from the sign.

Because of the low reflecting power of the ordinary painted surfaces for the light given off by the neon tube in the usual type of sign, practically the only light reaching the observer's eye is that which comes directly from the neon tube. Light is given off from the tube in all directions from its axis and consequently, if only the small portion of this direct light which is intercepted by the observer's eye can be considered useful, all that given off toward the sides and back of the tube is more or less wasted. In my construction, by reflecting the light given off from these latter portions, I utilize it to increase the effectiveness of the sign and the result is that a greater amount of light is reflected to the observer's eye with no increase in the electrical operating cost of the sign. This is in addition to the fact that the effectiveness of the sign as an advertising or display device is increased because the full-bodied letter which my invention produces is much more pleasing to the eye.

Some changes may be made in the construction and arrangement of the parts of my device without departing from the real spirit and purpose of my invention, and it is my intention to cover by my claims any modified forms of structure or use of mechanical equivalents, which may be reasonably included within their scope.

I claim as my invention:

1. In a gaseous tube sign letter, adapted to be mounted on a back board, a discharge tube formed in the shape of a letter, a reflector disposed rearwardly of said tube and having substantially the same letter shape as said tube, said reflector comprising a plurality of parallel reflector strips disposed at an angle to each other such that the directions of rays from the centers of said strips are substantially parallel, side elements for mounting the reflector to said back board comprising strips secured to the ends of the outermost of said reflectors directed backward toward said back board and bent into the form of an L forming a leg having a length equal to the distance between the center of said reflector to the outermost edges and means for securing the center of said reflector to said back board to draw said legs into supporting engagement therewith.

2. In a gaseous tube sign letter, a back board for supporting said letter having an aperture

- therein formed in the shape of said letter, a gaseous tube formed in the shape of said letter adapted to be positioned centrally of said aperture, a reflector disposed rearwardly of said tube having substantially the same letter shape as said tube, said reflector comprising a plurality of parallel reflecting strips located on the side and rear of said tube forming a reflecting surface extending the full width of said aperture, side elements for securing said reflecting surface therein comprising strips attached to the outermost end of the reflector and extending rearward into said aperture and having the free ends thereof bent angularly to provide a means for engaging the back wall at the rear face thereof.
5. In a gaseous tube display device, adapted to be mounted on a supporting surface, a discharge tube formed in any desired figure, a reflector disposed rearwardly of said tube, said reflector comprising a plurality of reflector strips on each side of said tube, said strips being disposed at angles to each other such that a discrete image of the tube is reflected from each strip to the eye of an observer in front of the device.
10. In a gaseous tube display device, adapted to be mounted on a supporting surface, a discharge tube formed in any desired figure, a reflector disposed rearwardly of said tube, said reflector comprising a plurality of reflector strips on each side of said tube, said strips being disposed at angles to each other such that the rays from said discharge tube are reflected from the centers of each of said reflecting strips in substantially parallel directions, and spacing elements extending rearwardly from said reflector, the free ends of said elements engaging the supporting surface.
15. In a gaseous tube display device, adapted to be mounted on a supporting surface, a discharge tube formed in any desired figure, and a reflector disposed rearwardly of said tube, spaced therefrom and having substantially the same figure
